UNITED STATES PATENT OFFICE.

GEORGE H. ROLFES, OF ST. LOUIS, MISSOURI, ASSIGNOR TO HANDLAN-BUCK MANUFACTURING COMPANY, OF ST. LOUIS, MISSOURI, A CORPORATION OF MISSOURI.

LANTERN-BURNER.

1,337,795.

Specification of Letters Patent.

Patented Apr. 20, 1920.

Application filed February 1, 1919. Serial No. 274,517.

To all whom it may concern:

Be it known that I, GEORGE H. ROLFES, a citizen of the United States of America, a resident of the city of St. Louis, in the 5 State of Missouri, have invented certain new and useful Improvements in Lantern-Burners, of which the following is a full, clear, and exact description, reference being had to the accompanying drawings, forming 10 a part of this specification.

My invention relates to a burner for use in railway lanterns, in the handling of which lanterns the flame from the burner is liable to become extinguished and burn 15 unevenly, due to suddenness and variety of motions given to the lantern, more particularly in signaling actions. The present invention is in the nature of an improvement upon the lantern burner shown and described in U. S. Letters Patent No. 1,276,417, issued to the Handlan-Buck Manufacturing Company August 20, 1918. The burner shown in said patent is so constructed as to 20 avoid extinction of a flame due to currents of air entering a lantern in which the burner is used, and the object of the present invention is the same as that shown in the patent, with the additional object in view of so constructing the burner as to baffle the air 25 currents and to avoid rapid movement of the air toward and around the flame produced in the burner, in order that the flame will burn evenly and uniformly under all 30 conditions.

Figure I is a top view of my burner on a lantern font.

Fig. II is a side elevation of the font and lower portion of the burner, the upper portion of the burner being in vertical section.

Fig. III is an elevation of the upper portion of the font, the burner being partly in elevation and partly in vertical cross section.

In the drawings A designates a lantern 45 font surmounted by a burner B, the body of which may be of any ordinary construction. The burner includes a wick tube b through with the wick C extends.

D designates a cup-shaped flame spreader 50 secured to the upper end of the wick tube b. This flame spreader is provided with parallel side walls 1, in each of which is an aperture 2 through which air may enter the flame spreader to supply oxygen to a flame 55 burning from the wick C. Each of the

side walls of the flame spreader has fixed to it a downwardly and outwardly flaring baffle wing 3, preferably perforated. The parts thus far described are shown in the patent herein mentioned and no invention 60 for such parts, *per se*, is herein claimed.

It has been found in the use of a burner having only the correlated parts just described, that when severe motion is imparted to a lantern in which the burner is 65 used, rapidly moving currents of air induced by the motion of the lantern enter beneath the baffle wings 3, moving both laterally and vertically, and pass into the flame spreader D to the detriment of an even 70 burning flame within the flame spreader. To avoid rapid flow of air currents into the flame spreader which interfere with the flame, I have in my present invention incorporated in the burner certain baffle members 75 which restrict and retard the flow of air currents, with the result of overcoming the interference with the burning of an even flame.

At each end of the burner is a transverse 80 baffle web 4 which preferably spans the space between the flaring baffle wings 3, said baffle webs being usually of the same height as each baffle wing, so that they prevent lateral or horizontal movement of air 85 between said baffle wings and the opposing walls of the flame spreader. 5 designates a horizontal baffle plate located beneath the flame spreader D and preferably formed with vertical extensions 6 which are suitably 90 secured to the baffle webs 4. This baffle plate 5 surrounds the wick tube C beneath the flame spreader and extends from the latter toward the lower edges of the baffle wings 3, from which it is separated suffi- 95 ciently to permit of the upward movement of air between the sides of the baffle plate 5 and the inner faces of the baffle wings 3. Provision is therefore made for the limitation of the amount of air permitted to ascend from beneath the burner to the flame spreader D, and such air as does ascend from beneath the burner must necessarily pass through the restricted passageways be- 100 tween the baffle wings 3 and the baffle plate 5, to be deflected by said baffle wings into the flame spreader. Therefore rapid and ununiform ascending air currents enter the flame spreader in an approximately hori- 105 zontal direction, and upon entering the 110

flame spreader do not materially interfere with the burning of the flame therein as they would if they were permitted to enter the flame spreader in a vertical direction and pass rapidly upwardly therein.

5 At each end of the flame spreader D is an outwardly flaring tip 7, these tips providing for elongation of the flame above the burner.

10 I claim:

1. A burner comprising a flame spreader having apertured walls, baffle wings extending downwardly from the upper portion of said flame spreader and overhanging the apertures in said walls, and baffle webs between said baffle wings extending downwardly from said flame spreader.

2. A burner comprising a flame spreader having apertured walls, baffle wings extending downwardly from the upper portion of said flame spreader and overhanging the apertures in said walls, and baffle webs spanning the spaces between said baffle wings and extending downwardly therebetween from said flame spreader.

3. A burner comprising a flame spreader having apertured walls, baffle wings extending downwardly from the upper portion of said flame spreader and separated from the apertured walls of the flame spreader, said baffle wings overhanging the apertures in said walls, and baffle webs extending downwardly from said flame spreader between said baffle wings.

35 4. A burner comprising a flame spreader having apertured walls, baffle wings flaring downwardly from the upper portion of said flame spreader and overhanging the apertures in said walls, and baffle webs extending downwardly from said flame spreader between the end portions of said baffle wings.

45 5. A burner comprising a flame spreader having apertured walls, baffle wings extending downwardly from the upper portion of said flame spreader and overhanging the apertures in said walls, baffle webs extending downwardly from said flame spreader be-

tween the end portions of said baffle wings, and a horizontal baffle plate beneath said flame spreader.

6. A burner comprising a flame spreader having apertured walls, baffle wings extending downwardly from the upper portion of said flame spreader and overhanging the apertures in said walls, baffle webs extending downwardly from said flame spreader between the end portions of said baffle wings, and a horizontal baffle plate beneath said flame spreader, said baffle plate being separated from said baffle wings.

7. A burner comprising a wick tube, a flame spreader having apertured walls, said flame spreader being secured to said wick tube, baffle wings extending downwardly from the upper portion of said flame spreader and overhanging the apertures in said walls, baffle webs extending downwardly from said flame spreader between the end portions of said baffle wings, and a baffle plate surrounding said wick tube and extending therefrom toward said baffle wings.

8. A burner comprising a wick tube, a flame spreader secured to said wick tube, said flame spreader having apertured walls, baffle wings flaring downwardly from the upper portion of said flame spreader and overhanging the apertures in said walls, baffle webs extending downwardly from said flame spreader between the end portions of said baffle wings, and a baffle plate surrounding said wick tube and extending horizontally therefrom toward said flaring baffle wings.

9. A burner comprising a flame spreader having apertured walls, baffle wings extending downwardly from the upper portion of said flame spreader and overhanging the apertures in said walls, and a horizontal baffle plate beneath said flame spreader.

In testimony that I claim the foregoing I hereunto affix my signature.

GEO. H. ROLFES.
